(57) **ABSTRACT**

Example embodiments relate to luminaire heads with interconnecting interfaces. One example luminaire head including an interconnected interface for an electronic device includes a support layer and a cover layer arranged over the support layer. The support layer includes a plurality of electrical tracks arranged on a surface of the support layer and connectable to a power supply of the luminaire head. The support layer also includes a first electrical connector. The first electrical connector is connected to at least one of the plurality of electrical tracks and is suited for connecting to the electronic device. Further, the support layer includes a second electrical connector. The second electrical connector is directly connected to the first electrical connector via

CROSS-REFERENCE TO RELATED APPLICATIONS

The present application is a national stage entry of PCT/EP2021/053543 filed Feb. 12, 2021, which claims priority to NL 2024888 filed Feb. 12, 2020, the contents of each of which are hereby incorporated by reference.

FIELD OF INVENTION

The field of the invention is related to a luminaire head comprising an interconnecting interface, and in particular an interconnecting interface comprising electrical tracks.

BACKGROUND

NL2022430 in the name of the applicant discloses a connection module for a luminaire with a light module, comprising a support, surge protection circuitry arranged on the support, a first and second supply terminal for connection to a power supply, said first and second supply terminal being connected to the surge protection circuitry, a first and second load terminal for connection to a drive means of the light module, said first and second load terminal being connected to the surge protection circuitry, and at least a first and second control terminal. A connection line for electrically connecting the first and second control terminal is arranged on the support. NL2022430 is included herein by reference.

Generally, luminaire heads assembly involves the gathering of multiple components such as electrical devices, cables and fixation means, in order to realize the desired electrical circuitry with the right functions. These numerous components can be placed in a compartment of the luminaire head, for example, and assembled together. Since typically, the volume within or around a luminaire head is limited, disposition of the different components is optimized and the assembly has generally to be done by following assembling steps in a particular order for every component to end up in place. However, when performing the first assembly or during maintenance, handling of cables and connections can be cumbersome due to the limited free space available and the inconvenience of managing a clear layout in the midst of a complex electrical circuit. This can cause in turn inaccuracies in the electrical connections and the mechanical fixations of the different components comprised in a luminaire head. Indeed, depending on the amount of components to be electrically connected inside the luminaire head for example, such as SPDs, control modules, LED drivers, power supply wires, fuses, varistors, and the like, a large number of wire harnesses to be created and maintained may be required, which may be long and cumbersome on the assembly lines at the manufacturing stage or during maintenance, and may increase the risk of causing wiring mistakes between the different components inside the luminaire head. Therefore, a luminaire head comprising an interconnecting interface is needed to facilitate the assembly and interconnection of some components which are part of the luminaire head.

It is known to provide a luminaire head with a gear compartment into which the multiple components composing the electrical circuitry of the luminaire head are placed. However, even well organized, the components are often placed over several "layers" and cable connections are

rendered complex, both in their layout and in their handling, increasing the probability of mishaps. Hence, there is a need for a luminaire head capable of decreasing the complexity and clutter of its electrical circuitry in order to prevent mistakes and facilitate maintenance.

SUMMARY

The object of embodiments of the invention is to provide 10 a luminaire head with an interconnecting interface capable of decreasing the difficulty in interconnecting some of the multiple components which are part of the electrical circuitry of the luminaire head, as well as decreasing the amount of clutter generated by it.

15 According to a first aspect of the invention there is provided a luminaire head comprising an interconnecting interface for an electronic device. The interconnecting interface comprises a support layer and a cover layer. The support layer comprises: a plurality of electrical tracks arranged on its surface and connectable to a power supply of the luminaire head; a first electrical connector, said first electrical connector being connected to at least one of the plurality of electrical tracks and being suited for connecting to the electronic device; and a second electrical connector, said second electrical connector being directly connected to the first electrical connector via the at least one of the plurality of electrical tracks. The cover layer is arranged over the support layer. An upper surface of the cover layer comprises a first opening forming passage for the first electrical connector, and comprises at least one retaining means configured for retaining in a removable manner the electronic device in electrical contact with the first electrical connector through the first opening. More in particular, the at least one retaining means may be configured for maintaining a plug or 20 a connector of the electronic device in electrical contact with the first electrical connector. Embodiments of the invention are based inter alia on the inventive insight that an electronic device being part of the luminaire head has its operating ability influenced by its mounting fixation strength and the 25 stability of its electrical connections. The inventors have discovered that, when assembling an electronic device as part of the luminaire head, the interconnections between the electronic device and other components composing the electrical circuitry of the luminaire head were prone to 30 vulnerability due to the many cumulative elements involved in the interconnections, e.g. connectors, wires. Due to space constraints, wires may be bended and space for manipulation cluttered, which may result in less-than-ideal interconnecting conditions.

35 40 45 50 55 60 By providing an interconnecting interface with properly laid out electrical tracks combined with electrical connectors, the number of elements in electrical interconnections to and/or from the electronic device can be reduced and they can be supplied directly with power from the power supply of the luminaire head. Additionally, using electrical tracks instead of wires produces a predictable usage of space having a fixed volume which decreases the clutter. The retaining means improves further the usability of the interconnecting interface by having the dual use of mechanical retention and insuring electrical connectivity, while providing ease of maintenance from its removable nature.

In a preferred embodiment, the electronic device is mounted on the cover layer or on the support layer.

In a typical embodiment, the retaining means may be any one of a friction means, a snap-fit means, a screwing means, a clipping means, a magnetic retaining means, and/or an adhesive. The support layer may be made in an electrically

insulating material. The skilled person will understand that the electrical tracks may be arranged on the support layer via various techniques, e.g. injection, deposition, adhesion. It is to be noted that the electronic device may be suited for cooperating with the retaining means or may be provided with a casing or additional parts, such as a mounting frame, a plugging element, an attaching element, suitable for cooperating with the retaining means. The first and second electrical connector may be female or male connectors, e.g. one or more protruding pins. The first and second electrical connector may be similar or may be different. For example, the first electrical connector may protrude outwardly from a surface of the support layer, and the second electrical connector may be configured for connecting on an opposite surface thereof. The cover layer and the support layer may be made of similar or different materials. The cover layer may be fixed to the support layer or may be fixed directly to the luminaire head. The cover layer may be provided with at least one indent configured for cooperating with the footprint of the electronic device. In order to protect the support layer adequately, the cover layer may cover at least 80%, preferably at least 90%, of the footprint of the support layer.

In a preferred embodiment, the luminaire head comprises a luminaire head housing, and the support layer is arranged on the luminaire head housing.

In this manner, the support layer is arranged in a predetermined location and may not require a specifically designed additional compartment. Depending on the shape of the luminaire head housing, the support layer may be adjusted to be suited to fit the housing dimensions and/or curvature. The support layer may be placed within the luminaire head housing to be better protected from the outside environment, or may be placed on an external surface of the luminaire head housing, optionally within a protective casing. In a typical embodiment, the luminaire head housing may be made of metal and the support layer may be in thermal contact with the luminaire head housing such that the luminaire head housing acts as a heat sink.

In an exemplary embodiment, the support layer and a portion of the luminaire head housing are molded in one piece. The portion of the luminaire head housing incorporating the support layer may be a cover portion of the luminaire head housing, said cover portion including a transparent or translucent material, or may be a main body portion of the luminaire head housing.

In this way, the luminaire head housing has a dual usage. It may allow employing fewer elements to interconnect the electronic device, which saves space and allows optimizing the volume available. The portion of the luminaire head with which the support layer is molded may be in an electrically insulating material. The rest of the luminaire head housing may be made of the same material or a different one.

In a favored embodiment, the support layer and/or the cover layer is at least 10 cm×10 cm, e.g. at least 15 cm×15 cm, or even at least 15 cm×30 cm.

In that manner, one or more components e.g. the electronic device may be supported on the cover layer and/or the support layer.

Preferably, the support layer and/or the cover layer structurally supports one or more of components e.g. the electronic device and/or a light module of the luminaire head. For example, the cover layer may support a LED array and/or a driver; or the cover layer may support the driver and the support layer may carry the LED array.

Additionally, the luminaire head may comprise another cover layer opposite the cover layer with respect to the support layer. The interconnecting interface may be further

configured for being connected to another electronic device, e.g. a LED array, on an opposite side of the support layer with respect to the electronic device, e.g. a driver.

In a possible embodiment the electrical tracks may be tracks similar to tracks used on a PCB, in which case the tracks may be relatively thin, e.g. below 100 microns. However, in other embodiment the tracks may be punched or cut out of a metal sheet. In such an embodiment the tracks may be relatively thick. For example, the electrical tracks may have a thickness between 0.25 mm and 1 mm, more preferably between 0.35 mm and 0.70 mm. Such tracks provide additional rigidity and are suitable for large currents.

In a preferred embodiment, the portion of the luminaire head housing is an external wall of the luminaire head housing.

In this manner, the interconnecting interface may be made more accessible and the internal layout of the luminaire head housing, for example, may be simplified.

In an exemplary embodiment, the at least one retaining means and the cover layer are molded in one piece.

In this way, the at least one retaining means is located in a predetermined place. Since the at least one retaining means is integrated to the cover layer, the number of elements required for the assembly of the luminaire head components may be decreased. The cover layer and the at least one retaining means may be formed, e.g. by injection molding, casting, transfer molding or in another appropriate manner. Preferably, the at least one retaining means is located next to the opening in the cover layer to be adapted to electronic devices having reduced footprints. The at least one retaining means may be a mechanical retaining means, a magnetic retaining means, and/or an adhesive.

In a preferred embodiment, the at least one retaining means is a mechanical retaining means, preferably a snap-fit retaining means.

In this manner, the design of the at least one retaining means may be simplified, and the retaining function may be more reliable. The retaining means may be any one of a friction means, a snap-fit means, a screwing means, a clipping means. The mechanical retaining means may be assisted or completed by additional retaining means, mechanical or non-mechanical. In one embodiment, the opening in the cover layer may be surrounded by a wall forming a plug and the electronic device may be provided with a complementary plug and retained by friction when plugged.

In a typical embodiment, the at least one retaining means may be a snap-fit retaining means made of an elastic material, e.g. plastic, and comprise at least one snap-fit member extending outwardly with respect to the cover layer. In another embodiment, the at least one retaining means may comprise at least one or more pairs of members located on opposite sides of the opening to securely retain the electronic device. Additionally or alternatively, the electronic device may be enclosed in a casing with snap-fit retaining means and provided to the cover layer, said snap-fit retaining means being adapted for cooperating with corresponding recesses of the cover layer.

In an exemplary embodiment, the cover layer may be provided with one or more structural elements which are molded in one piece with the cover layer. Such structural elements may have a mechanical function or a marking function or an identifying function. For example, a structural element may have a retaining or guiding or positioning function, or may indicate where a component should be located or connected on the cover layer, or may be provided with a identification means, etc.

In an exemplary embodiment, a cable organizer, such as a clip may be provided to the cover layer. The cable organizer may be mounted to the cover layer or may be integral to the cover layer. In a preferred embodiment, the cable organizer may be molded in one piece with the cover layer. The cable organizer may be configured for retaining and/or guiding and/or positioning one or more cables or wires extending e.g. to and from the electronic device, such that said one or more cables or wires are better organized. For example, the cable organizer may be a simple bracket dimensioned and shaped such that one or more cables can be arranged below the bracket.

Additionally or alternatively, the cover layer may be provided with embossing or engravings for indicating information to a user of the luminaire head, such as caution messages, component indications, mounting information, etc. Also, the cover layer may be provided with recesses facilitating the placing of components on the cover layer.

In an exemplary embodiment, the electronic device is one of: a driver, e.g. a lighting driver, a sensing means, a processing means, a transmission means, a communication means, a metering device, an electrical protection means, e.g. an ESD protection device, a filtering unit, a surge protection device, a fuse, a varistor, a control module, a light module, an indicator means, such as a LED indicator, or other active or passive electronic components/parts.

In this way, at least one of the essential components of a luminaire head may have dedicated interconnections.

In a preferred embodiment, the interconnecting interface comprises the electronic device provided to it.

In an exemplary embodiment, the electronic device is embedded in a packaging.

In this manner, the electronic device may be protected from the surrounding environment. The packaging may be designed for being adapted to the at least one retaining means and/or to cooperate with the first electrical connector. The packaging may be one integrally molded element.

In a preferred embodiment, the cover layer is in contact with the plurality of electrical tracks.

In this way, the overall volume of the interconnecting interface can be reduced and the plurality of electrical tracks may be better protected from the surrounding environment. The cover layer may be a rigid cover layer or may be a flexible cover layer. The cover layer may be fabricated separately and then arranged over the support layer, or may be applied directly to the support layer. The cover layer may be made of a polymeric material, e.g. polymeric resin.

Alternatively, the cover layer is at a distance of less than 5 mm, preferably less than 3 mm, more preferably less than 1 mm from the plurality of electrical tracks. Doing so may provide for some margin space not to impede thermal expansion of different materials while still obtaining a compact assembly of the support layer and the cover layer.

In an exemplary embodiment, the upper surface of the cover layer comprises a guiding means surrounding the first opening and configured for guiding the connection of the electronic device with the first electrical connector through the first opening.

In this manner, the electrical connection may be more secure and reproducible, and allows for an easy assembly. Additionally, the guiding means may improve the positioning accuracy of the electronic device. In an embodiment, the guiding means may be a wall surrounding the opening in the cover layer and form a plug. The guiding means and the at least one retaining means may be formed integrally to decrease the number of separate elements and optimize the functions of the interconnecting interface.

In a preferred embodiment, the guiding means is configured for engaging the packaging of the electronic device.

In this way, the guiding means and the packaging of the electronic device may be designed in a limited number of variants, and optimized for automated assembly procedures.

In an exemplary embodiment, the plurality of electrical tracks is submerged in one piece consisting of the cover layer and the support layer.

10 In this manner, the interconnecting interface is provided with supplementary integral parts which improve the solidity, the simplicity, and the reliability of the interconnecting interface.

In a preferred embodiment, the upper surface of the cover layer comprises a second opening forming passage for the second electrical connector.

15 In this way, multiple components may be connected to the upper surface of the interconnecting interface, further optimizing its usability as a space saver.

20 In an exemplary embodiment, the electronic device, when connected to the at least one electrical connector, is removable, preferably in a tool-less manner, from within the luminaire head housing.

25 In this manner, maintenance is facilitated when replacing the electronic device for example.

In a preferred embodiment, the luminaire head comprises a light module electrically connected to the interconnecting interface.

30 In a typical embodiment, the light module comprises a plurality of light sources, e.g. LEDs e.g. organized in an array, disposed on a substrate, e.g. a PCB, and the substrate may be supported and/or maintained on the cover layer and/or the support layer. Alternatively, the light sources may be arranged directly on the cover layer and/or the support layer. For example, the LEDs may be arranged in a planar array and the plurality of electrical tracks may extend in a plane substantially parallel to said planar array. Additionally or alternatively, the electronic device may be a driver enclosed in a housing and the housing may be supported and/or maintained on the cover layer.

35 In this way, the main function of a luminaire, lighting, may be connected to the interconnecting interface. The interconnecting interface may thus provide an interconnecting hub for the luminaire head. The main functions of the luminaire head may be reliably assembled and the layout of the assembly optimized. Additionally, the layout of the interconnecting interface may be optimized for automated assembly procedures.

40 In an exemplary embodiment, the second electrical connector is suited for connecting to another electronic device.

45 In this manner, more components may be provided to the interconnecting interface and the volume and clutter of the luminaire head may be further decreased. The another electronic device may be one of: a driver, e.g. a lighting driver, a sensing means, a processing means, a transmission means, a communication means, a metering device, an electrical protection means, e.g. an ESD protection device, a filtering unit, a surge protection device, a fuse, a varistor, a control module, or other active or passive electronic components/parts.

50 In a preferred embodiment, the support layer further comprises a third electrical connector, said third electrical connector being connected to at least one of the plurality of electrical tracks, preferably further comprises a fourth electrical connector, said fourth electrical connector being connected to at least one of the plurality of electrical tracks, and more preferably further comprises a fifth electrical connec-

tor, said fifth electrical connector being connected to at least one of the plurality of electrical tracks.

In a typical embodiment, the first electrical connector is connected to a driver, and, optionally, the second electrical connector is connected to a light module, the third electrical connector is connected to a sensing means, the fourth electrical connector is connected to a surge protection device, and the fifth electrical connector is connected to a controller socket, e.g. NEMA socket, Zhaga socket, low voltage socket. The skilled person will understand that the terms "first", "second", "third", "fourth", and "fifth" are merely indicative and do not restrict the connection of each of the components to a specific electrical connector.

In this way, the usage of the interconnecting interface may be further optimized, improving the integration of the different components of the luminaire head.

According to another aspect of the invention there is provided a luminaire system including: a power supply, and a luminaire head comprising an interconnecting interface for an electronic device. The luminaire head of the luminaire system may be the luminaire head of any of the hereinabove described luminaire head embodiments. The power supply is connected to a plurality of electrical tracks arranged on a surface of the support layer included in the interconnecting interface of the luminaire head. The skilled person will understand that the hereinabove described technical considerations and advantages for luminaire head embodiments also apply to the above mentioned corresponding luminaire system embodiments, mutatis mutandis.

BRIEF DESCRIPTION OF THE FIGURES

This and other aspects of the present invention will now be described in more detail, with reference to the appended drawings showing a currently preferred embodiment of the invention. Like numbers refer to like features throughout the drawings.

FIGS. 2A and 2B schematically illustrate a partially transparent top perspective view and a bottom perspective view, respectively, of a luminaire head comprising an interconnecting interface according to another exemplary embodiment of the invention;

FIG. 3 schematically illustrates a close-up perspective view of an electrical connector connected to an electronic device according to an exemplary embodiment of the invention;

FIGS. 4A and 4B schematically illustrate a typical luminaire head and a luminaire head according to another exemplary embodiment of the invention, respectively;

FIGS. 5A and 5B schematically illustrate close-up views of portions of an interconnecting interface according to an exemplary embodiment of the invention;

FIGS. 6A-6D schematically illustrate various electrical connectors suitable for an interconnecting interface according to an exemplary embodiment of the invention;

FIG. 7 schematically illustrates a portion of a luminaire head with a cable organizer according to an exemplary embodiment of the invention.

DESCRIPTION OF THE FIGURES

FIGS. 1A and 1B schematically illustrate a cut side-view and an exploded perspective view, respectively, of an inter-

connecting interface and a portion of a luminaire head according to an exemplary embodiment of the present invention. The luminaire head comprises an interconnecting interface 100 for an electronic device 200. The interconnecting interface 100 comprises a support layer 110 and a cover layer 120 arranged over the support layer 110.

The support layer 110 comprises a plurality of electrical tracks 111 arranged on a surface of the support layer 110. The plurality of electrical tracks 111 may be made out of an electrically conducting material, e.g. metal. The plurality of electrical tracks 111 may be provided via chemical etching, evaporation, deposition, injection, molding, gluing or other appropriate methods. In some embodiments, the tracks may be arranged in a similar way as on a PCB. However, in other embodiments, the tracks may be cut out of, e.g. punched of a metal sheet and have a thickness between 0.25 mm and 1 mm, e.g. between 0.35 mm and 0.70 mm. The plurality of electrical tracks 111 are connectable to a power supply (not shown) of the luminaire head, e.g. battery, mains. The skilled person will understand that the plurality of electrical tracks 111 and the power supply may be electrically connected via any known means, e.g. soldering to electrical pads, via a dedicated electronic connector, etc.

The support layer 110 below the plurality of electrical tracks 111 may be made out of an electrically insulating material. In an embodiment, the support plate 110 and the plurality of electrical tracks 111 may form a printed circuit board assembly, PCBA.

The support layer 110 may be arranged on a surface portion of the luminaire head. This surface portion of the luminaire head may be located within a luminaire head housing 300 or outside of the luminaire head housing 300. The support layer 110 may be fixed to the luminaire head housing 300 via various fixation means. Depending on the surface portion of the luminaire head onto which the support layer 110 is arranged, the shape of the support layer 110 may be adapted according to predetermined dimensions and curvature. The support layer 110 may be arranged in a specific compartment, such as a gear compartment, or may be arranged directly on a portion of a wall of the luminaire head housing 300, e.g. on a portion of an external wall of the luminaire head housing 300. Depending on the material of the surface portion of the luminaire head, the surface portion in thermal contact with the support layer 110 may act as a heat sink. The rest of the luminaire head may be made in the same material or in a different material as the surface portion of the luminaire head. In an embodiment, the surface portion of the luminaire head may be made of an electrically-conductive material, and there may be an electrical insulation layer between the support layer 110 and the surface portion of the luminaire head.

The support layer 110 comprises a first electrical connector 112 and a second electrical connector 113. The first electrical connector 112 is connected to at least one of the plurality of electrical tracks 111. The first electrical connector 112 may comprise one or more connecting elements, three connecting elements in the embodiment of FIGS. 1A-1B. The first electrical connector 112 may comprise male and/or female elements for electrically connecting with a first complementary electrical connector 212. In the embodiment of FIGS. 1A-1B, the first electrical connector 112 comprises three outwardly protruding pins. Each connecting element comprised in the first electrical connector 112 may be connected to the same or different electrical tracks. In another embodiment, the first electrical connector 112 may comprise a different number of connecting elements.

The first electrical connector 112 is suited for connecting to the electronic device 200. The electronic device 200 may comprise the first complementary electrical connector 212, or the first complementary electrical connector 212 may be provided separately to the electronic device 200. The electronic device 200 may be any one of: a driver, e.g. a lighting driver, a sensing means, a processing means, a transmission means, a communication means, a metering device, an electrical protection means, e.g. an ESD protection device, a filtering unit, a surge protection device, a fuse, a varistor, a control module, or other active or passive electronic components/parts. Optionally, the electronic device 200 may be embedded in a packaging 210, or provided with a casing such that it is better protected from the surrounding environment. The packaging 210 or casing may allow an easier connection of the first electrical connector 112 and the first complementary electrical connector 212.

At least one connecting element of the first electrical connector 112 is connected to the second electrical connector 113 via at least one of the plurality of electrical tracks 111. The second electrical connector 113 may comprise one or more connecting elements, one connecting element in the embodiment of FIGS. 1A-1B. The second electrical connector 113 may comprise male and/or female elements for electrically connecting with a second complementary electrical connector. The second electrical connector 113 may be configured to be connected to the same side or to an opposite side of the support layer 110 as the first electrical connector 112, to the same side in the embodiment of FIGS. 1A-1B.

The cover layer 120 is arranged over the support layer 110. In the embodiment of FIGS. 1A-1B, the cover layer 120 is fixed over the support layer directly to the luminaire head housing 300 and the internal surface of the cover layer 120 is at a distance of the support layer 110. Depending on embodiments, the cover layer 120 may be at a distance of less than 5 mm, preferably less than 3 mm, more preferably less than 1 mm from the plurality of electrical tracks 111. In another embodiment, the support layer 110 is fixed to the cover layer 120. The support layer 110 and the cover layer 120 may be made of similar or different materials. The support layer 110 and the cover layer 120 may be made in one piece for example. In still another embodiment, the cover layer 120 is made of a polymer, e.g. a polymeric resin, directly applied on the support layer 110 and the plurality of electrical tracks 111 is submerged below this cover layer. In yet another embodiment, the plurality of electrical tracks 111 may be submerged in one piece consisting of the cover layer 120 and the support layer 110, by multi-shot injection molding for example. In yet another embodiment, the cover layer 120 and the support layer 110 may be integrated in a portion of the external wall of the luminaire head housing 300 and the plurality of electrical tracks 111 may be submerged within it.

An upper surface of the cover layer 120 comprises a first opening 121 forming passage for the first electrical connector 112. The first opening 121 may comprise a through-hole surrounding the one or more connecting elements of the first electrical connector 112. The upper surface of the cover layer 120 comprises also at least one retaining means 122 configured for retaining in a removable manner the electronic device 200 in electrical contact with the first electrical connector 112 through the first opening 121. The at least one retaining means 122 may be a mechanical retaining means, a magnetic retaining means, and/or an adhesive, preferably a mechanical retaining means. The at least one retaining means 122 may be separately provided from the cover layer 120 or may be integrally molded with the cover layer.

In the embodiment of FIGS. 1A-1B, the at least one retaining means 122 and the cover layer 120 are molded in one piece, and the at least one retaining means 122 comprises a pair of snap-fit members protruding outwardly on either side of the first opening 121. The cover layer 120 and the at least one retaining means 122 may be made in a material with some elasticity, e.g. plastic, in order for the at least one retaining means 122 to retain the electronic device 200 in a removable manner, preferably in a tool-less manner.

10 The packaging 210 of the electronic device of FIGS. 1A-1B is provided with corresponding indents 211 such that, when the electronic device 200 is pushed in between the pair of snap-fit members, the snap-fit members will, in a first phase, spread open before getting closer and fit within the corresponding indents 211 to retain the packaged electronic device 200. In this manner, the electrical connection of the first electrical connector 112 and the first complementary electrical connector 212 may be maintained securely.

In a favored embodiment, a cable organizer, e.g. a clip 20 (not shown) may be provided to the cover layer 120. The cable organizer may be mounted to the cover layer 120, e.g. using snap-fit member as disclosed above, or may be integral with, i.e. molded in one piece with the cover layer 120. The cable organizer may be configured for retaining one or more cables or wires, e.g. extending to and from the electronic device, such that said one or more cables or wires are better organized. Additionally or alternatively, the cover layer 120 may be provided with embossing or engravings for indicating information to a user of the luminaire head, such as 25 caution messages, component indications, mounting information, etc. Also, the cover layer 120 may be provided with recesses facilitating the placing of components on the cover layer 120. Further, the cover layer may be provided with an integral identification means, such as a unique code, e.g. a 30 QR code.

To help the connection of the electronic device 200 and the first electrical connector 112, a guiding means 123 may be provided. The guiding means 123 may surround the first opening 121. In the embodiment of FIGS. 1A-1B, the 40 guiding means 123 comprises a wall extending outwardly from the upper surface of the cover layer 120 and defines a plug. The packaging 210 of the electronic device may comprise a corresponding recess as a complementary guiding means defining a socket. In another embodiment, the 45 guiding means 123 may comprise a rail element configured for cooperating with an external surface of the electronic device 200 such that a user may connect the electronic device 200 by simply sliding the electronic device 200 into place guided by the rail element. Additionally or alternatively, the guiding means 200 may double as a retaining means by using friction to retain the electronic device 200 50 electrically connected. In still another exemplary embodiment, the guiding means 200 and the at least one retaining means 122 may be molded in one piece to further optimize 55 the different portions of the interconnecting interface 100.

Supplementary electrical connectors 112, 113, electronic devices 200, and corresponding openings 121 in the cover layer 120 may be added to the interconnected interface 100 to form a more complex electrical circuit interconnecting 60 various electrical components of the luminaire head. For example, a light source connected to the interconnecting interface 100 may be comprised in the luminaire head.

FIGS. 2A and 2B schematically illustrate a partially transparent top perspective view and a bottom perspective view, respectively, of a luminaire head comprising an interconnecting interface according to another exemplary embodiment of the present invention. The luminaire head

11

2000 comprises an interconnecting interface **2100** for multiple electronic devices **2200**, **2300**, **2400**. The interconnecting interface **2100** comprises a support layer and a cover layer.

In the embodiment of FIGS. 2A-2B, the cover layer and the support layer of the interconnecting interface **2100** may be integrally formed and integrated in a portion of an external wall of the luminaire head housing. The interconnecting interface **2100** may comprise a plurality of electrical tracks **2110a**, **2110b**, **2110c**, **2110d**, **2110e** which are submerged within the support layer and the cover layer, for example by multi-shot injection molding. The plurality of electrical tracks **2110a**, **2110b**, **2110c**, **2110d**, **2110e** may be arranged in a plane, said plane virtually defining the cover layer on one side facing the multiple electronic devices **2200**, **2300**, **2400**, and defining the support layer on the other side of the plane opposite the cover layer. Depending on embodiments, the support layer is at least 10 cm×10 cm, preferably at least 15 cm×15 cm, more preferably at least 15 cm×30 cm.

The plurality of electric tracks **2110a**, **2110b**, **2110c**, **2110d**, **2110e** may be made in an electrically conductive material, e.g. in metal, and the portion of the external wall may be made in an electrically insulating material, e.g. in plastic. The portion of the external wall comprising the interconnecting interface **2100** may be integrally formed with the rest of the luminaire head housing external wall or separately formed.

The interconnecting interface **2100** may comprise a first electrical connector **2120**, a second electrical connector **2125**, a third electrical connector **2130**, a fourth electrical connector **2143a**, **2143b**, and a fifth electrical connector **2150**. One or more electrical connectors of the plurality of electrical connectors **2120**, **2125**, **2130**, **2143a**, **2143b**, **2150** may be similar. The plurality of electrical connectors **2120**, **2125**, **2130**, **2143a**, **2143b**, **2150** may be interconnected via the plurality of electrical tracks **2110a**, **2110b**, **2110c**, **2110d**, **2110e**. In the embodiment of FIGS. 2A-2B, the fourth electrical connector **2143a**, **2143b** is linked to the first electrical connector **2120** via two different electrical tracks **2110a**, **2110b**. Each of the two different tracks **2110a**, **2110b** may be connected separately via two separate connecting elements **2143a**, **2143b** on the side of the fourth electrical connector. Two electrical tracks **2110c** link the first electrical connector **2120** to the third electrical connector **2130**. And three electrical tracks **2110d** link the third electrical connector **2130** to the second electrical connector **2125**. The electrical track **2110e** may be linked to the fifth electrical connector **2150** connected to the ground. More details on the fifth electrical connector **2150** can be found with respect to FIG. 5A. In another embodiment, the plurality of electrical tracks **2110a**, **2110b**, **2110c**, **2110d**, **2110e** may be grounded via another means, e.g. via a soldered wire connected to the ground. Thus, different electrical components of the luminaire head may be interconnected via the interconnecting interface **2100**. The skilled person will understand that the plurality of electrical tracks and the plurality of electrical connectors may be arranged in a different manner in order to interconnect the different electrical components for constructing the desired electrical circuit.

At least one among the plurality of electrical connectors **2120**, **2125**, **2130**, **2143a**, **2143b** may be suited for connecting to an electronic device **2200**, **2300**, **2400**. In the embodiment of FIGS. 2A-2B, the electronic device **2200** may be a driver enclosed in a casing **2210** configured for being connected to the first and second electrical connectors **2120**, **2125** via a first complementary and a second complementary

12

electrical connectors **2225** (only the second is visible). Details on the connection between the second electrical connector **2125** and the second complementary electrical connector **2225** may be found with reference to FIG. 3.

5 The electrical connectors may be male or female. For example, the first electrical connector **2120** of FIGS. 2A-2B may comprise a plurality of connecting elements, two rows of four female connecting elements, and the second electrical connector **2125** may comprise another plurality of connecting elements, one row of four female connecting elements. The fourth electrical connector **2143a**, **2143b** may be configured for being connected to a light module **2300**.

In the embodiment of FIGS. 2A-2B, the third electrical connector **2130** may comprise tool-reliant or tool-less connecting elements, and may be configured to be connected to a power supply, such as the mains. The third electrical connector **2130** may be connected to the power supply via an electrical cable **2500**. The cover layer of the interconnecting interface **2100** may comprise a cable retaining

10 means **2160** configured for retaining an electrical cable. In the embodiments of FIGS. 2A-2B, the cable retaining means **2160** is configured for retaining the electrical cable **2500** of the power supply such that it faces the third electrical connector **2130**. The cable retaining means **2160** may comprise an electrical cable seat **2161**, and a cable retainer **2162**. More details on the cable retaining means **2160** can be found with respect to FIG. 5B.

15 The electronic device **2200** and/or the light module **2300** may be retained in a removable manner in electrical contact with the corresponding electrical connectors **2120**, **2125**, **2143a**, **2143b** via at least one retaining means, a plurality of retaining means **2141a**, **2141b**, **2142** in FIGS. 2A-2B. The at least one retaining means **2141a**, **2141b**, **2142** may include a mechanical retaining means, a magnetic retaining means, and/or an adhesive.

20 The first and second electrical connectors **2120**, **2125** may be provided each with a guiding means to help the connection of the corresponding first and second electrical connectors **2225** of the electronic device **2200**.

25 The light module **2300** of FIGS. 2A-2B may comprise a support plate **2330**, e.g. a PCB, with a plurality of light sources **2310**, e.g. a plurality of LEDs, arranged thereon. The plurality of LEDs **2310** may be provided with a corresponding plurality of optical elements **2320** placed over them. The plurality of optical elements **2320** may be integrally formed in a plate, for example a lens plate. The plurality of optical elements **2320** may be fixed to the support plate **2330** and guided into place via guiding pins **2144** of the interconnecting interface **2100**. The support plate **2330** may be fixed independently from the plurality of optical elements **2320** to the interconnecting interface **2100**.

30 The light module **2300** of FIGS. 2A-2B may be retained by a plurality of snap-fit retaining means **2141a**, **2141b**, with four snap-fit members located on each side of the light module **2300** in the embodiment of FIGS. 2A-2B, and guided and oriented into place by the guiding pins **2144** going through the light module **2300**. More in particular, in the embodiment of FIGS. 2A-2B, two opposing members **2141a** of the four snap-fit members of the snap-fit retaining means are configured for retaining the support plate **2330** of the light module, and the other two opposing members **2141b** of the four snap-fit members of the snap-fit retaining means are configured for retaining the plurality of optical elements **2320**. The skilled person will understand that the number of snap-fit retaining means may be adapted to characteristics of the electronic device or component to be retained. The casing **2210** enclosing the electronic device

2200 is retained via a snap-fit retaining means **2142** with two snap-fit members located on either side of the casing **2210**. The plurality of retaining means **2141a**, **2141b**, **2142** may be integrally formed with the portion of the luminaire head external wall.

In another non-illustrated embodiment, the light module **2300** and the plurality of optical elements **2320** may be provided on the support layer, i.e. on a lower surface of the interconnecting interface **2100**. Instead of arranging the LEDs **2310** on a support plate **2330** it is also possible to arrange the LEDs directly on the cover layer or on the support layer, and to omit the support plate **2330**.

The fourth electrical connector **2143a**, **2143b** comprises in FIGS. 2A-2B two separate connecting elements. The two separate connecting elements consist each in a recess exposing at least one of the plurality of electrical tracks **2110a**, **2110b**. Facing the fourth electrical connector **2143a**, **2143b**, the support plate **2330** of the light module comprises on its lower surface connecting protrusions **2343a**, **2343b** configured to lodge in the corresponding recesses and to electrically connect the plurality of LEDs **2310** arranged on the support plate **2330** to at least one of the plurality of electrical tracks **2110a**, **2110b**. Hence, the electronic device, e.g. a driver, a sensing means, a surge protection device, connected to the third electrical connector **2130**, and the light module **2300**, may be easily interconnected and assembled to the interconnecting interface **2100** comprised in the luminaire head to perform one of the main functions of a luminaire, lighting.

In the embodiments of FIGS. 2A-2B, the electronic device **2400** may include a fuse holder holding at least one fuse. The fuse holder may be retained in a removable manner to the cover layer of the interconnecting interface **2100** via a pair of DIN rails **2170**. The pair of DIN rails **2170** may be integrated to the cover layer of the interconnecting interface **2100**.

According to another aspect of the invention there is provided a luminaire system including the power supply, and the luminaire head comprising the interconnecting interface **2100**. The luminaire head of the luminaire system may be the luminaire head of any of the hereinabove described luminaire head embodiments. The power supply may be connected to the plurality of electrical tracks **2110a**, **2110b**, **2110c**, **2110d**, **2110e** included in the interconnecting interface **2100** of the luminaire head. The skilled person will understand that the plurality of electrical tracks **2110a**, **2110b**, **2110c**, **2110d**, **2110e** and the power supply may be electrically connected via any known means, e.g. soldering to electrical pads, via a dedicated electronic connector, etc.

FIG. 3 schematically illustrates a close-up perspective view of an electrical connector connected to an electronic device according to an exemplary embodiment of the present invention.

With reference to FIGS. 2A-2B, the electronic device **2200** may be a driver enclosed in a casing **2210** configured for being connected to the first and second electrical connectors **2120**, **2125** via a first complementary and a second complementary electrical connectors **2220**, **2225**. In the embodiment of FIG. 3, the second electrical connector **2125** is connected to the second complementary electrical connector **2225**.

The second electrical connector **2125** is connected to at least one of the plurality of electrical tracks **2110d** submerged in the interconnecting interface **2100**. To reach electrical contact, the second electrical connector **2125**, which is a female-type connector, and the second comple-

mentary electrical connector **2225**, which is a male-type connector, may be plugged together.

In the embodiment of FIG. 3, the second complementary electrical connector **2225** comprises a plurality of contacting pins **2227** extending downwards towards the connecting interface and configured to be plugged in corresponding recesses **2126** of the second electrical connector **2125**. The plurality of corresponding recesses **2126** of the second electrical connector acts as a guiding means for the connection. The plurality of corresponding recesses **2126** are formed in an upper surface of a guiding protrusion **2127** extending away from the interconnecting interface.

The guiding protrusion **2127** is provided with a mechanical retaining means **2128**, more particularly a snap-fit retaining means. The mechanical retaining means **2128** comprises a wall extending at a distance from the guiding protrusion **2127** and substantially in parallel to it. The mechanical retaining means **2128** of the guiding protrusion presents a lip on its upper end extending towards the guiding protrusion **2127**. The second complementary electrical connector **2226** comprises a corresponding mechanical retaining means **2228** comprising a wall extending at a distance from the plurality of contacting pins **2227** and substantially in parallel to them. The corresponding mechanical retaining means **2228** of the connecting pins **2227** presents a lip on its lower end extending away from the connecting pins **2227**.

When plugging the second electrical connector **2125** and the second complementary electrical connector **2225**, the mechanical retaining means **2128** of the guiding protrusion **2127** is spread away from the guiding protrusion **2127**. The corresponding mechanical retaining means **2228** of the connecting pins, when plugged, has its lip retained by the lip of the mechanical retaining means **2128** of the guiding protrusion, effectively maintaining the electrical contact of the connecting pins **2227** with at least one of the plurality of electrical tracks **2110d** via the recesses **2126** of the guiding protrusion **2127**. The electronic device is thus mounted to the cover layer.

Optionally, the connecting pins **2227** may be provided with upper connecting elements accessible from the top of the casing **2210** to allow connecting an additional module to the driver, for example, via a slot **2230** in the casing **2210** of the driver.

FIGS. 4A-4B schematically illustrate a typical luminaire head and a luminaire head according to another exemplary embodiment of the present invention, respectively.

A luminaire head generally comprise a light module **44** with support, typically a PCB, and at least one light source arranged thereon, a driver **43** configured for driving the at least one light source, a surge protection device (SPD) **42** between a power supply **41** and the driver **43**. Typically, the at least one light source of the light module **44** comprise a plurality of LEDs connected in series and/or in parallel.

The driver **43** for the at least one light source of the light module **44**, typically in the form of a LED driver, may be arranged in or on a luminaire head **400**, in or on the luminaire pole, or in any other suitable location of a luminaire system. The SPD **42** is provided in order to leverage the benefit of long life of the at least one light source of the light module **44**, typically a plurality of LEDs. The SPD **42** protects the driver **43** against surge events. The driver **43** may be configured to convert an AC voltage in a DC drive current for the at least one light source of the light module **44**.

In FIG. 4A, the SPD **42** is connected in series. When connected in series, a first and second power terminal are connected to a first and a second power supply line leading

to the power supply 41, and a third and fourth power terminal are connected to a third and a fourth power supply line leading to the driver 43. In another embodiment, the SPD 42 may be connected in parallel.

As illustrated in FIG. 4B, an interconnecting interface 45 comprised in a luminaire head 400 may comprise at least four electrical connectors, said plurality of electrical connector each being connected to at least one of a plurality of electrical tracks. In the embodiment of FIG. 4B, the first electrical connector is connected to the power supply 41, the second electrical connector is connected to the driver 43, the third electrical connector is connected to the light module 44, and the fourth electrical connector is connected to the surge protection device 42. The plurality of electrical tracks may interconnect at least two electrical components among the SPD 42, the driver 43, and the light module 44. The SPD 42 may be enclosed in a housing and the housing of the SPD 42 may be supported and/or maintained on a cover layer of the interconnecting interface 45. In another embodiment, the driver 43 may be enclosed in a housing and the housing of the driver 43 may be supported and/or maintained on the cover layer of the interconnecting interface 45. In yet another embodiment, the light module 44 may be supported and/or maintained on the cover layer of the interconnecting interface 45. In still another embodiment, the interconnecting interface 45 may be part of an external wall of the luminaire head 400 housing, and the SPD 42, the driver 43, and the light module 44 may be all supported and/or maintained on the said part of the external wall.

FIGS. 5A and 5B schematically illustrate close-up views of portions of an interconnecting interface according to an exemplary embodiment of the present invention.

FIG. 5A illustrates a partially transparent top view of the fifth electrical connector 2150 referred to with respect to FIGS. 2A-2B. The fifth electrical connector 2150 may be connected to the rest of the electrical circuit via the electrical track 2110e submerged in the interconnecting interface 2100. The electrical track 2110e may be connected to a conductive exposed annular portion 2151 of the fifth electrical connector 2150. The conductive exposed annular portion 2151 may be configured for being in electrical contact with a metallic portion of the luminaire head housing. The conductive exposed annular portion 2151 may include a plurality of serrated teeth 2152 extending downwardly and towards the center of the conductive exposed annular portion 2151. The plurality of serrated teeth 2152 may be configured for improving the electrical contact between the portion of the luminaire head housing and the fifth electrical connector 2150. The conductive exposed annular portion 2151 may be provided with a central passage 2153. The central passage 2153 may be configured for enabling a bolt to pass through such that the interconnecting interface 2100 can be attached to the portion of the luminaire head housing. By establishing the electrical contact between the interconnecting interface 2100 and the luminaire head housing, and by attaching them one to another, the electrical circuit connected to the fifth electrical connector 2150 via the electrical track 2110e may be provided with a ground.

FIG. 5B illustrate a cut side-view of the cable retaining means 2160 referred to with respect to FIGS. 2A-2B. The cable retaining means 2160 may be configured for retaining an electrical cable 2500, e.g. the electrical cable of the power supply, such that it faces a corresponding electrical connector. In this manner, precision and reliability of the electrical contact at the level of the electrical connector may be improved. The cable retaining means 2160 may comprise the electrical cable seat 2161 and the cable retainer 2162.

The electrical cable seat 2161 may be integrated to the outer surface of the cover layer of the interconnecting interface 2100. In the embodiment of FIG. 5A, the electrical cable seat 2161 includes a pair of parallel tabs extending away from the outer surface of the cover layer of the interconnecting interface 2100. Each of the pair of parallel tabs may be provided on its outer surface with a saw-tooth profile. The cable retainer 2162 may be provided with a central opening. The central opening of the cable retainer 2162 may be configured for being engaged with the pair of parallel tabs of the electrical cable seat 2161 and for cooperating with the saw-tooth profile. When cooperating with the electrical cable seat 2161, the cable retainer 2162 may restrain the electrical cable 2500 from leaving the electrical cable seat 2161 within each it is provided. Due to the saw-tooth profile of the electrical cable seat 2161, the cable retainer 2162 may be prevented from being removed from the electrical cable seat 2161, thereby insuring the fixed position of the electrical cable 2500.

FIGS. 6A-6D schematically illustrate cut side-views of various electrical connectors suitable for an interconnecting interface according to an exemplary embodiment of the invention.

In the embodiments of FIGS. 6A-6D, an interconnecting interface 6100 of a luminaire head may comprise a plurality of electrical tracks 6111. The plurality of electrical tracks 6111 may be submerged within the interconnecting interface 6100. The plurality of electrical tracks 6111 may be connected in electrical contact with an electronic device (not shown) thanks to an electrical connector linked to at least one of the plurality of electrical tracks 6111 connecting to a corresponding connecting element linked to the electronic device.

In the embodiment of FIG. 6A, the electrical connector connected to the at least one of the plurality of electrical tracks 6111 includes a connecting recess 6120a and an exposed portion of electrical track included within the connecting recess 6120a. The corresponding connecting element connected to the electronic device may be a knife connector 6220a made in a conductive material. The knife connector 6220a may be configured for cutting into the section of the exposed portion of electrical track within the connecting recess 6120a when pushed against it, thereby establishing electrical connection between the plurality of electrical tracks 6111 and the electronic device.

In the embodiment of FIG. 6B, the electrical connector connected to the at least one of the plurality of electrical tracks 6111 includes a connecting spring 6120b extending away from a cover layer of the interconnecting interface 6100. The connecting spring 6120b may comprise a pair of tabs. The pair of tabs of the connecting spring 6120b may be integrally formed with the at least one of the plurality of electrical tracks 6111. The corresponding connecting element connected to the electronic device may include an external terminal 6220b surrounding a connecting passage 6220b', said connecting passage 6220b' going through a support of the electronic device. The external terminal 6220b may be made of a conductive material. The connecting spring 6120b and the external terminal 6220b may cooperate and be electrically connected by snap-fitting the connecting spring 6120b through the connecting passage 6220b'.

In the embodiment of FIG. 6C, the electrical connector connected to the at least one of the plurality of electrical tracks 6111 includes an outwardly protruding connecting pin 6120c. The outwardly protruding connecting pin 6120c may follow a C-profile in order to allow a sideway electrical

connection. The corresponding connecting element connected to the electronic device may comprise a push-in connector 6220c. The push-in connector 6220c may be located on a side of a support of the electronic device. When mounting the electronic device into place, the outwardly protruding connecting pin 6120c may be slid from the side of the electronic device within the push-in connector 6220c, thereby establishing electrical connection between the plurality of electrical tracks 6111 and the electronic device.

In the embodiment of FIG. 6D, the electrical connector connected to the at least one of the plurality of electrical 5 6111 includes an outwardly protruding connecting pin 6120d. The corresponding connecting element connected to the electronic device may include a connecting passage 6220d, said connecting passage 6220d going through a support of the electronic device. The connecting passage 10 6220b' may be internally coated with a conductive material. Electrical connection between the connecting passage 6220d and the outwardly protruding connecting pin 6120d 15 may be achieved thanks to a laser welding 6220b.

FIG. 7 schematically illustrates a portion of a luminaire head with a cable organizer according to an exemplary embodiment of the present invention. It may be the luminaire head illustrated in FIGS. 1A-1B or FIGS. 2A-2B. The cable organizer 124, such as a clip may be provided to the cover layer 120. The cable organizer 124 may be mounted to the cover layer 120 or may be integral to the cover layer 120, integral to the cover layer in FIG. 7 and molded in one piece with the cover layer 120. The cable organizer 124 may be configured for retaining and/or guiding and/or positioning one or more cables or wires 500 extending e.g. to and from the electronic device, such that said one or more cable or wires 500 are better organized. For example, the cable organizer 124 may be a simple bracket dimensioned and shaped such that one or more cables or wires 500 can be arranged below the bracket. In the embodiment, the cable organizer 124 comprises a fixed end 124a fixed to the cover layer 120 and a free end 124b such that the one or more cables or wires 500 can be arranged under a middle portion of the cable organizer 124 from the free end 124b side.

Additionally or alternatively, the cover layer 120 may be provided with embossing or engravings for indicating information 125 to a user of the luminaire head, such has caution messages, component indications, mounting information, etc. Also, the cover layer 120 may be provided with recesses (not shown) facilitating the placing of components on the cover layer 120.

Whilst the principles of the invention have been set out above in connection with specific embodiments, it is to be understood that this description is merely made by way of example and not as a limitation of the scope of protection which is determined by the appended claims.

The invention claimed is:

1. Luminaire head comprising an interconnecting interface for an electronic device, said interconnecting interface comprising:

a support layer comprising:

a plurality of electrical tracks arranged on a surface of the support layer and connectable to a power supply of the luminaire head;

a first electrical connector, said first electrical connector being connected to at least one of the plurality of electrical tracks and being suited for connecting to the electronic device; and

a second electrical connector, said second electrical connector being directly connected to the first electrical connector via the at least one of the plurality of electrical tracks; and

5 a cover layer arranged over the support layer, wherein an upper surface of the cover layer comprises a first opening forming passage for the first electrical connector and at least one retaining means configured for retaining in a removable manner the electronic device in electrical contact with the first electrical connector through the first opening.

2. The luminaire head according to claim 1, further comprising a luminaire head housing,

10 wherein the support layer is arranged on the luminaire head housing, and

15 preferably, wherein the electronic device, when connected to the first electrical connector and when the support layer is placed within the luminaire head housing, is removable from within the luminaire head housing.

3. The luminaire head according to claim 2, wherein the support layer and a portion of the luminaire head housing are 20 molded in one piece, and

25 preferably, wherein the portion of the luminaire head housing is an external wall of the luminaire head housing.

4. The luminaire head according to claim 1, wherein the at least one retaining means and the cover layer are molded in one piece.

5. The luminaire head according to claim 1, wherein the at least one retaining means is a mechanical retaining means, 30 preferably a snap-fit retaining means.

6. The luminaire head according to claim 1, wherein the support layer and the cover layer are molded in one piece.

7. The luminaire head according to claim 1, wherein the support layer is at least 10 cmx10 cm, preferably at least 15 35 cmx15 cm, more preferably at least 15 cmx30 cm.

8. The luminaire head according to claim 1, wherein the electronic device is one of: a driver, a sensing means, a processing means, a transmission means, a communication means, a metering device, an electrical protection means, a filtering unit, a surge protection device, a fuse, a varistor, a control module, or other active or passive electronic components.

9. The luminaire head according to claim 1, further comprising the electronic device provided to the interconnecting interface and supported by the cover layer or the support layer, and, preferably, wherein the electronic device is embedded in a packaging.

10. The luminaire head according to claim 1, wherein the cover layer is in contact with the plurality of electrical tracks, or

45 wherein the cover layer is at a distance of less than 5 mm, preferably less than 3 mm, more preferably less than 1 mm from the plurality of electrical tracks.

11. The luminaire head according to claim 1, wherein the upper surface of the cover layer comprises a guiding means surrounding the first opening and configured for guiding the connection of the electronic device with the first electrical connector through the first opening, and, preferably, wherein the guiding means is configured for engaging the packaging of the electronic device.

12. The luminaire head according to claim 6, wherein the plurality of electrical tracks is submerged in one piece consisting of the cover layer and the support layer.

13. The luminaire head according to claim 1, wherein the upper surface of the cover layer comprises a second opening forming passage for the second electrical connector.

19

14. The luminaire head according to claim 1, further comprising a light module electrically connected to the interconnecting interface, and preferably, wherein the light module comprises a LED array provided to the support layer or the cover layer.

15. The luminaire head according to claim 1, wherein the second electrical connector is suited for connecting to another electronic device.

16. The luminaire head according to claim 1, wherein the support layer further comprises a third electrical connector, said third electrical connector being connected to at least one of the plurality of electrical tracks, and preferably further comprises a fourth electrical connector, said fourth electrical connector being connected to at least one of the plurality of electrical tracks, and more preferably further comprises a fifth electrical connector, said fifth electrical connector being connected to at least one of the plurality of electrical tracks.

17. The luminaire head according to claim 16, wherein the first electrical connector is connected to a driver, and, optionally, wherein the second electrical connector is connected to a light module, wherein the third electrical connector is connected to a sensing means, wherein the fourth electrical connector is connected to a surge protection device, and wherein the fifth electrical connector is connected to a controller socket.

18. The luminaire head according to claim 1, wherein one or more structural elements, such as a cable organizer, are molded in one piece with the cover layer.

19. Luminaire head comprising an interconnecting interface for an electronic device, said interconnecting interface comprising:

a support layer comprising:

a plurality of electrical tracks arranged on a surface of the support layer and connectable to a power supply of the luminaire head;

a first electrical connector, said first electrical connector being connected to at least one of the plurality of electrical tracks and being suited for connecting to the electronic device; and

a second electrical connector, said second electrical connector being directly connected to the first electrical connector via the at least one of the plurality of electrical tracks;

a cover layer arranged over the support layer; and a luminaire head housing, wherein the support layer is arranged on the luminaire head housing, wherein the support layer and a portion of the luminaire head housing are molded in one piece, and wherein an upper surface of the cover layer comprises a first opening forming passage for the first electrical connector.

20. Luminaire head comprising an interconnecting interface for an electronic device, said interconnecting interface comprising:

a support layer comprising:

a plurality of electrical tracks arranged on a surface of the support layer and connectable to a power supply of the luminaire head;

a first electrical connector, said first electrical connector being connected to at least one of the plurality of electrical tracks and being suited for connecting to the electronic device; and

a second electrical connector, said second electrical connector being directly connected to the first electrical connector via the at least one of the plurality of electrical tracks; and

a cover layer arranged over the support layer, wherein an upper surface of the cover layer comprises a first opening forming passage for the first electrical connector, and

wherein the cover layer is in contact with the plurality of electrical tracks or the cover layer is at a distance of less than 5 mm, preferably less than 3 mm, more preferably less than 1 mm from the plurality of electrical tracks.
